UNITED STATES PATENT OFFICE.

ROBERT SCHLEGELMILCH, OF ARTERN, GERMANY, ASSIGNOR OF ONE-HALF TO AKTIEN-MASCHINENFABRIK "KYFFHÄUSERHÜTTE" VORM. PAUL REUSS, OF ARTERN, GERMANY.

CHIMNEY-TOP.

SPECIFICATION forming part of Letters Patent No. 766,735, dated August 2, 1904.

Application filed December 8, 1903. Serial No. 184,345. (No model.)

To all whom it may concern:

Be it known that I, ROBERT SCHLEGELMILCH, director, a subject of the German Emperor, and a resident of Artern, in the Kingdom of 5 Prussia, German Empire, have invented certain new and useful Improvements in Chimney-Tops, of which the following is a specification.

The subject of the present invention constitutes an improvement in chimney-tops with a turning cap in which a support built into the chimney is provided with a bearing-socket covered at the top and closed at the bottom, in which rotates a spindle held by a ring and 10 acting as a pivot, whereby the bearing-socket forms a permanent lubricating-bearing. The innovation consists in the arrangement that the ring is rigidly fixed on the spindle, so that the latter acts as a piston and protects the cap 15 against being blown down by a storm. At the same time the friction is not distributed over the circumference of the spindle, but over the circumference of the ring.

The drawing represents a form of construction of such a chimney-top in a longitudinal section.

The bearing-socket *h* is affixed to the support *a* and receives the axle *i*, fixed to the cap *g*. The axle *i*, which, with its point *k*, acts 20 as a pivot, carries at a suitable height a bearing-ring *m*, closely fitting in the socket *h*, so that the bearing at this place acts as a spindle-bearing and gives to the cap a steady move-

ment. The free space *r* between the socket and the axle *i* is filled in the usual manner with 35 a suitable lubricant offering a sufficient resistance to the influences of the temperature and weather, so that all the friction-surfaces remain constantly greased and their wear and tear is reduced to a minimum. The bearing 40 is consequently permanently lubricated. As the space *r* is filled with a lubricant and the ring *m* closely fits in *h*, a resistance is opposed to the withdrawal of the axle *i* from the socket, as in that case a vacuum formed then below 45 the ring *m* would have to be overcome.

What I claim as my invention, and desire to secure by United States Letters Patent, is—

A chimney-top with a turning cap having a bearing-socket affixed to a support *a* in which 50 socket, closed at the bottom and covered over at the top, rotates a spindle laterally held in position by a ring and at the top fixed to the cap, said ring being rigidly fixed on the spindle for the purpose of causing the latter to act 55 in the manner of a piston in the space below the ring and thereby prevent the cap from being blown down by a storm, substantially as and for the purpose set forth.

The foregoing specification signed at Berlin 60 this 25th day of November, 1903.

ROBERT SCHLEGELMILCH.

In presence of—

WOLDEMAR HAUPT,
HENRY HASPER.
